ARCH SUPPORT

Joseph Guy, Quincy, Mass.

Application April 7, 1954, Serial No. 29,893

Term of patent 14 years

(Cl. D7—5)

Fig. 1

Fig. 2.

To all whom it may concern:

Be it known that I, Joseph Guy, a citizen of the United States, and a resident of Quincy, in the county of Norfolk and Commonwealth of Massachusetts, have invented a new, original, and ornamental Design for an Arch Support, of which the following is a specification, reference being had to the accompanying drawing, forming a part thereof.

In the drawing:

Fig. 1 is a top plan view of an arch support embodying my new design; and

Fig. 2 is a left side view.

I claim:

The ornamental design for an arch support, substantially as shown.
